CHRISTIAN GEERTSEN, OF SCOTIA, NEW YORK.

FOLDING STOOL.

Application filed August 26, 1927. Serial No. 215,781.

This invention relates to folding stools and contemplates a construction made up of a plurality of pivotally mounted sections capable of being folded in parallelism to provide 5 a comparatively small article which can be conveniently carried from place to place, and also capable of being extended to provide a stool of considerable height, the invention residing in the construction, combination and 10 arrangement of parts as claimed.

In the drawings forming part of this application like numerals of reference indicate similar parts in the several views and wherein:

- 15 Figure 1 is a view of the stool folded.
- Figure 2 is a similar view taken at a right angle to Figure 1.
- Figure 3 is a view showing the stool partly unfolded.
- 20 Figure 4 is a view showing the stool set up for use.
- Figure 5 is a perspective view of one of the main sections.
- Figure 6 is a sectional view on line 6—6 25 of Figure 5.

The stool forming the subject matter of the present invention comprises a pair of crossed pivotally connected main sections 10 and 11 respectively, each section being substantially 30 U-shaped as shown in Figure 6. The corresponding upper ends of these sections have secured thereto a sleeve 12 about which are looped the adjacent ends of a flexible seat 13. These sections are pivoted upon a rod 14 adjacent their lower ends, while the limbs of 35 each section are provided with laterally extending offset hooks 15 for a purpose to be hereinafter described. These sections are of relatively different lengths, although sub- 40 stantially of the same length, being so constructed to permit the section 11 to fold within the section 10. When so arranged the looped extremities of the flexible seat are arranged directly one above the other, the seat 45 being folded upon itself to hang at one side as clearly shown in Figure 2. The sections are adapted to be extended for use as clearly illustrated in Figures 3 and 4, and when so extended the stool is supported in a manner 50 to be presently described.

For this purpose I make use of a supporting section 16 which is substantially U-shaped and pivoted on the rod 14 outwardly of the main section 10, thereby allowing this section 55 16 to also be folded in parallelism with the seat sections as shown in Figure 1. When

so folded the section 16 has its cross member 17 arranged directly above the looped portions of the seat, being spaced therefrom so that the section 16 can be used as a handle to 60 conveniently carry the stool from place to place.

Also pivoted upon the rod 14 inwardly of the main section 11 is a supporting member substantially U-shaped, but made up of two pivotally connected sections 18 and 19 respectively, the former having its outer ends terminating to provide laterally offset hooks 20, to engage the section 19 when the parts are extended as shown in Figure 4. The section 19 is capable of being folded between the limbs of the section 18, and this section is then adapted to be folded within the main section 11 as shown in Figures 1 and 2. Consequently when the seat is folded, the various 70 sections are folded one within the other, lying in the same plane, and in a manner to provide a comparatively small article which can be conveniently carried by the person, or conveniently located beneath the seat of an 80 automobile or the like.

In order to use the stool it is only necessary to extend the main sections 10 and 11 as shown in Figure 3 moving the supporting section 16 upon its pivot beyond the section 10, and also moving the supporting member including the sections 18 and 19 beyond the seat section 11. The section 16 is swung about its pivot and over the supporting member including the sections 18 and 19, until the 90 limbs of the section 16 are engaged by the hooks of the main seat section 10, thereby forming a continuity of this section as illustrated in Figure 4. The limbs of the section 18 of the other supporting member are then 95 moved into engagement with the hooks 15 of the section 11, while the section 19 of said supporting member is swung outwardly to engage the hooks 20 of the section 18. The stool is then in a set up position for use, and 100 when it is desired to fold the stool the various sections can be quickly and easily folded one within the other in the manner hereinabove described.

While it is believed that from the foregoing 105 description, the nature and advantages of the invention will be readily apparent, I desire to have it understood, that I do not limit myself to what is herein shown and described and that such changes may be resorted to 110 when desired as fall within the scope of what is claimed.

What is claimed is:

A folding stool comprising a pair of crossed pivotally connected main sections adapted to fold one within the other, a flexible seat secured to the adjacent upper ends of said sections, offset hooks projecting from the lower ends of said sections, a substantially U-shaped supporting section pivotally mounted on the pivot of the main sections and adapted to be folded in parallelism with said sections, and constituting a handle for the stool when the latter is folded, said supporting section forming a continuity with one of the main sections when the stool is set up and adapted to be engaged by the hooks of said main section, a supporting member of substantially U-shaped formation pivotally mounted on the same pivot and including pivotally connected sec-

tions adapted to be arranged in end to end relation to form a continuity with the other main section for use, one section of the supporting member being engaged by the hooks of its respective main section when extended, laterally extending hooks formed on said section of the supporting member and adapted to engage the other section of the supporting member when said section is extended, said latter mentioned section being adapted to fold within the first mentioned section of the supporting member, and said supporting member being adapted to fold within one of the main sections in parallelism with the aforementioned other main section.

In testimony whereof I affix my signature.

CHRISTIAN GEERTSEN.
